United States Patent Office

Des. 222,185
Patented Oct. 5, 1971

222,185

MAIL BOX

Irving A. Levine, 37 W. 12th St., New York, N.Y. 10011

Filed June 2, 1970, Ser. No. 23,257

Term of patent 14 years

Int. Cl. D31

U.S. Cl. D74—9

FIG. 1

FIG. 2

FIG. 3

FIG. 1 is a perspective view of a mail box showing my new design.

The side opposite to the side shown presents a similar appearance as the side disclosed in FIG. 1, except for the flag.

FIG. 2 is a top plan view thereof.

FIG. 3 is a rear view thereof as it appears with the flag in lowered position.

I claim:

The ornamental design for a mail box, as shown and described.
